US00D870181S

(12) **United States Design Patent** (10) **Patent No.:** **US D870,181 S**
(45) **Date of Patent:** **** Dec. 17, 2019**

(54) **SURVEILLANCE CAMERA**

(71) Applicant: **Honeywell International Inc.**,
Morristown, NJ (US)

(72) Inventors: **Junwei Geng**, Shanghai (CN); **Yun Li**,
Shanghai (CN); **Dezhi Yang**, Shanghai
(CN)

(73) Assignee: **Honeywell International Inc.**, Morris
Plains, NJ (US)

(**) Term: **15 Years**

(21) Appl. No.: **29/650,902**

(22) Filed: **Jun. 11, 2018**

(51) LOC (12) Cl. **16-01**

(52) U.S. Cl.

(57) **CLAIM**

The ornamental design for a surveillance camera, as shown
and described.

DESCRIPTION

FIG. 1 is a front perspective view of a surveillance camera
showing the new design;

FIG. 2 is a front elevation view thereof.

FIG. 3 is a rear elevation view thereof.

FIG. 4 is a right side elevation view thereof, the left side
elevation view being a mirror image thereof; and,

FIG. 5 is a bottom plan view thereof.

The broken lines in the drawings depict subject matter of the
surveillance camera that forms no part of the claimed design.
The top view of the surveillance camera forms no part of the
claimed design

1 Claim, 3 Drawing Sheets
